UNITED STATES PATENT OFFICE.

WALTER F. BARCH, OF WASHINGTON, DISTRICT OF COLUMBIA, ASSIGNOR TO
KEUFFEL & ESSER CO., OF HOBOKEN, NEW JERSEY, A CORPORATION OF NEW
JERSEY.

FOUNTAIN LETTERING-PEN.

1,367,346.

Specification of Letters Patent.

Patented Feb. 1, 1921.

Application filed November 10, 1920. Serial No. 423,021.

To all whom it may concern:

Be it known that I, WALTER F. BARCH, a citizen of the United States, residing at 511 10th St. N. W., Washington, District of Columbia, have invented certain new and useful Improvements in Fountain Lettering-Pens, of which the following is a specification.

My invention relates to improvements in 10 lettering or marking pens, and is adapted to hold a quantity of ink so as to avoid the necessity of refilling during the drawing of a line. The invention consists in the adaptation and arrangement of the parts as herein- 15 after fully set forth.

In the accompanying drawings Figure 1 is a top plan view; Fig. 2 is a side view; Fig. 3 is a bottom plan view; and Fig. 4 is a section on the line 4—4 of Fig. 1.

Referring to the drawings 5 is a pen having nibs 6 and 7 separated by an opening 8 between said nibs. The pen 5 is mounted in the usual way in a holder 9.

An ink holding means 10 is cut out of the 25 upper side of the nibs 6 and 7 on each side of the opening 8 so that when the ink holding means 10 is filled with ink it will flow down through the opening 8 to the ends of the nibs 6 and 7, which are curved down- 30 wardly and terminate in semi-circular beveled surfaces 11 and 12.

A thumb screw 13 having a knurled head 14 is mounted in a threaded bore 15 passing through said nibs 6 and 7, so as to vary the 35 width of the opening 8 upon the adjustment of said thumb screw 13.

In using the pen herein described, ink will 40 first be placed in the containing means 10 and the thumb screw 13 adjusted so as to obtain the proper width of the opening 8, which will vary the width of the line required, and the ink will flow as the pen is used from the containing means 10 through the opening 8 to the semi-circular beveled

surfaces 11 and 12 of the nibs 6 and 7, thereby giving a line of uniform width with a continuous flow of ink. 45

It will be apparent that the form of pen disclosed herein is so constructed that it can be easily and quickly cleaned without the necessity of taking the same apart. 50

I claim:

1. In a lettering pen the combination of two substantially rigid nibs having beveled termini forming a substantially circular 55 writing surface, an ink holding means formed in the upper side of said nibs and means for varying the width of opening between said nibs.

2. In a lettering pen the combination of 60 a body portion having two substantially rigid nibs with a slight opening between, said nibs terminating in a substantially circular beveled plane marking surface, an ink holding means formed in the upper side of 65 said nibs on each side of said opening, and a thumb screw passing through said nibs at right angles to said opening adapted to vary the amount of said opening.

3. In a lettering pen the combination of a 70 body portion, two substantially rigid nibs terminating in a substantially circular beveled plane, means in said pen for holding ink, and means for adjusting the opening between said nibs. 75

4. In a lettering pen the combination of a body portion, two substantially rigid nibs terminating in a substantially circular beveled plane, means in said pen for holding ink, and means for adjusting the opening 80 between said nibs consisting of a thumb screw.

In testimony whereof I affix my signature in presence of two witnesses.

WALTER F. BARCH.

Witnesses:

JOHN H. SIGGERS,
DAVID R. WAGNER.
